(57) **CLAIM**

The ornamental design for a bath filler, as shown and described.

DESCRIPTION

FIG. 1 is a left, top, front perspective view of a bath filler according to the new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line representations in the figures are for the purpose of illustration only, and form no part of the claimed design. The broken line representation of the hose portion shown in FIG. 1 has been omitted from the remaining figures so as not to obstruct those views of the claimed design.

Portions of the spout and standpipe are shown separated by break lines to illustrate an indeterminate length. The precise length of those portions is not being claimed.
